DEVICE FOR SEPARATING RAISINS FROM FOREIGN MATTER

Filed Feb. 23, 1927

Inventor:

William Stoner
by Francis G. Schueber,
Attorney.

UNITED STATES PATENT OFFICE.

WILLIAM STONER, OF FRESNO, CALIFORNIA.

DEVICE FOR SEPARATING RAISINS FROM FOREIGN MATTER.

Application filed February 23, 1927. Serial No. 170,111.

My invention relates to a device for picking foreign matter out of raisins. It is well known among those versed in the manufacture and packing of raisins, that when the 5 raisins are brought to the packing house from the vineyards, it is frequently true that there are many small stones and foreign substances therein, such as nails, pieces of wood, and metal box corners. The raisin stock is 10 usually run over a screen or shaker, which removes the larger stones, sticks, nails and substances, and frequently magnets are placed in the path of travel of the raisin stock to pick out the metal which may be 15 attracted thereto, but there yet remains in the raisins some pieces of metal and stones the approximate size of the raisins, and smaller, and imperfect raisins produced from immature grapes which are termed in 20 the trade "red berries", these red berries being hard and unfit for food. Such foreign matter not only injures the machinery through which the raisins are required to pass, but the red berries, stones and foreign 25 material remaining in the commercial pack of raisins diminish the value of raisins as a food product. It has heretofore been the practice to run raisins which contain many small stones or nails through a sluice box 30 and bath. When sent through the sluice box the baffles will catch the nails and stones and the raisins will be floated over the baffles, and in the bath the good raisins sink to the bottom and the red berries will float 35 on the top where they can be removed. But by the use of the sluice box or the bath it is necessary to re-dry the raisins. This is not only expensive but requires considerable time, and when it is necessary to manufacture 40 raisins in a hurry, these steps are omitted. When they are subjected to the water treatment it leaves the raisins sticky and gummy and in an inferior class to those which have not been subjected to the water 45 process.

In the device which I have invented the stones and other foreign matter, and red berries, are sorted out of the general mass of raisins. The object of my device is to separate raisins from foreign matter and from 50 red berries.

This object and other objects hereinafter referred to are accomplished by means of a device hereinafter described and illustrated

in the accompanying drawing, in which 55 Figs. 1, 2, 3 are perspective views of different forms of rollers which may be used in my device. Fig. 4 is a side view of my device partly in section. Fig. 5 is a detail view of the adjustable partition. Fig. 6 60 shows screw means for adjusting the proximity of the rollers.

In the drawing 7 is a roller in which the periphery is covered with a yielding material such as soft rubber, or a gelatine mixture such as is commonly used on rollers for inking printing presses, or it may be formed of other yielding material such as soft leather. Working opposite is a roller 8 composed of hard substances such as metal, 65 wood or other equivalent. These rollers are adapted to rotate on their axes and are set so the peripheries are quite near together. In the drawing 9 is a beam which carries the rollers described, 9^a being the frame supporting beams 9, 10 representing the bearing in which the axle 11 of the hard roller 8 is carried, and 12 the bearing which carries the axle 13 of the soft roller 7. Bearing 12 is attached to a slide 21 on beam 9, and the 70 adjustment of the soft roller in relation to the hard roller is made by screw 14. Said screw 14 operates through a female screw 15, the female screw being attached to the frame 9 and the bearing 12 being attached 75 by a ball and socket joint 22 to the end of screw 14. It will be noted that by turning the screw 14 in one direction it will position the roller 7 towards the rigid roller 8, and by turning it in the opposite direction it will 80 position the soft roller away from the rigid roller. This turning may be done by a handle 14^a.

It is here noted that the bearings and adjusting screws should be in pairs, one 95 on each end of the axle, although but one of each pair is shown in the drawing.

The rollers are adapted to rotate in opposite directions shown by arrows 22 and 23. It will be noted that the portions of the peripheries adjacent to each other when the two rollers are assembled for operative relation will turn in a downward direction. Directly between the two rollers and under them, I have placed a vertical partition 24, 100 the purpose of the partition being to guide the good raisins which fall on one side in a different direction from the stones and hard 105

raisins or red berries which fall on the opposite side. The top edge 25 of the partition 24 should be very thin and the top line of said partition should be approximately parallel with the shafts which carry the rollers. The shafts of the rollers should be adjusted parallel to each other. Partition 24 should be constructed so that it can be adjusted vertically and laterally, and it should be held rigidly in the position to which it has been adjusted. For this purpose I have formed extensions of wings 70 on the lower end of the partition, the wings having slots 71 therein. A support 72 is provided for each wing, the support being a part of the frame 9. Pivotal members 75 are attached to the wall 72 and extend through the slots 71 so that the partition 24 can be swung on a radius from the pivots 75, and the wing members and partition attached can be moved horizontally on the pivots the limits of said slots. By this device the partition can be adjusted approximately to the position desired, and by means of winged nuts 76 the wings can be clamped to the pivots in the position desired. For the purpose of making finer adjustments the partition 24 is laterally divided into two parts, 24^a and 24^b, which are hinged together, and by means of a threaded adjusting screw 77, operating through a female screw 78, the upper portion 24^a of the partition can be moved forward or back as desired. Screw 77 should be attached to the upper portion 24^a, through a slot 80. This slot permits the partition to be adjusted vertically and at the adjustment desired the screw is clamped to the partition with nut 81.

It is here noted that when a conglomeration of stones, nails and other foreign substances and raisins are passed between said rollers when the rollers are being rotated, the soft raisins will adhere to the hard roller, and the stones, nails and red berries or hard raisins, being harder than the yielding roller, will sink into the soft yielding material on the periphery of roller 7 while being passed between said rollers, and then be carried by this device beyond the vertical dividing line between the two rollers, at which line the top edge of the partition 25 is positioned. The raisins passed through said rollers are thus separated, the soft pliable raisins following the hard roller beyond said dividing line and dropping on the side of partition 24 on which the hard roller is positioned and the stones and red berries, nails, and all objects harder than the good raisins follow the soft roller 7 and dropping on the side of partition 24 on which the soft roller is positioned.

I cannot herein give the proven theory whereby the foregoing results are accomplished inasmuch as several different theories on the subject seem reasonable although not

conclusive, but through experiments which I have been making for a number of years I have made the discovery that the functions of the soft or yielding roller with the hard roller produces the results herein set forth. 70

My experiments have shown that the hard roller can be constructed with smooth periphery as shown in Fig. 2, although better results are accomplished if the periphery of the hard roller has small corrugations 75 therein. These corrugations can be lateral as shown in Fig. 3, or they can encircle the roller as shown in Fig. 1.

In my experiments I prefer that the hard roller have the corrugations encircling the 80 periphery as shown in Fig. 1 for the reason that if the raisins should be sufficiently sticky to adhere to the roller they can be more easily released from the roller by having the fingers 30 shown in Fig. 4 engage the 85 periphery of the roller and function as a scraper. The soft roller can be moistened if desirable to coact against the sticky quality of the raisins.

It is further noted that the yieldable 90 roller preferably has a smooth periphery, although a corrugated periphery could be used, and that the thickness of the yieldable portion of roller 7 may be in thickness from approximately one-half inch upward. My 95 preference is not less than one inch thickness of such covering if a hard roller is to be used as a base to carry the soft covering. It is here noted that a flexible covering for roller 7 which is held expanded by pneumatic means can be substituted for the soft rubber. 100

The speed at which the rollers should rotate depends upon the diameter of the rollers. The travel speed of the peripheries may be 105 varied from approximately two feet per second upward. In some of my experiments I used rollers having equal diameters, although rollers of different diameters can be used to advantage in cleaning some raisins. My discovery broadly is that when raisins containing matter in which there are particles harder than the raisins, by running them between two rollers, one of which has a yielding periphery and the other a rigid periphery, the soft raisins will preferably follow the roller having the rigid periphery and the harder particles will follow the roller having the yielding periphery. 110 115

Commercial raisins naturally have a soft 120 flabby texture and are in condition to be processed by running between the rollers as described, but if the raisins should be bone dry, they can be softened by steaming or by placing them in a room having high humidity, which will condition them for processing.

In my experiment it has been disclosed that running the uncleaned raisins between the rollers one time will frequently separate 130

all of the stones, red berries and foreign substances from the raisins, but that without accurate adjustments of the proximity of the peripheries of the two rollers, and the accurate adjustment of the dividing partition, some good raisins will get into the refuse compartment and some stones will get into the raisin compartment. In order, therefore, to simplify my machine to obviate these difficulties, and fine adjustments, I have constructed a machine illustrated in Fig. 3 in which three pairs of rollers are positioned one below the other, and the adjustments are made so that the inaccuracies of the machine will dispose of portions of the raisins into the refuse compartment rather than to drop the stones and kindred substances into the cleaned raisin compartment. This can be done by adjusting the dividing partition so that it is slightly nearer to the hard roller than it is to the soft roller. I then run the deposits in the refuse compartment between another series of rollers. In Fig. 3 I have shown an arrangement of this character of three pairs of rollers positioned in a vertical stack.

In said Fig. 3, an assembly of the rollers 40 is shown at the top, an assembly of rollers 50 is shown in the center, and an assembly 30 of rollers 60 is shown at the bottom. Each set or assembly of rollers has an adjustable partition 24 hereinbefore described. Each assembly has a chute 31, which chute is placed on the side of the partition on which the hard roller is positioned, each of said chutes being positioned on an incline downward from the partition and entering a common discharge pipe 32. The upper pair of rollers indicated as 40 and the middle 40 pair of rollers indicated as 50 have refuse chutes 35 positioned directly under the soft rollers. The refuse chute directs the flow of stones, refuse and such raisins as may not have been sorted out when passing through the first roller assembly to the top of the roller assembly 50 which is directly underneath, and by similar mechanism and procedure the good raisins are separated from the mass and are conducted to the discharge pipe. The refuse and such raisins not yet separated from the mass are then conducted to, and passed through roller assembly 60. The assembly of rollers 60 has under the soft roller a chute 36 which directs the stones and hard berries and foreign matter to a container 49. A hopper 51 is positioned above the top of assembly 40 which directs

the flow of raisins between the rollers forming roller assembly 40.

With proper skill being exercised in the 60 adjustments, one, or a combination of two, roller assemblies will perform the work of sorting satisfactorily. Under other conditions a larger number than 3 of such roller assemblies may be desirable. 65

The means for rotating said rollers can be by a pulley or toothed wheel 44 attached to each hard surfaced roller and aligned and a common belt or chain 41 adapted to engage each of said pulleys or wheels. The 70 roller having the soft periphery could be rotated by proximity to roller having the hard periphery. Other means may be used.

It is further noted that occasionally the 75 raisins are very sticky and will adhere to the roller. The fingers 30 have been referred to as one means for cleaning the rollers, but the moistening of the rollers assists in keeping them clean. As moistening rollers is old and no claim is herein made for 80 such moistening, no means for performing such function is shown.

Having described my invention I claim:

1. In a device of the character described the combination of a roller having a hard corrugated periphery and a roller having a soft yielding periphery adapted to rotate with the peripheries in close proximity so that the portion of the two peripheries nearest each other pass in a downward direction, 90 and a partition having a diminished upper edge positioned so that said upper edge is aligned on an approximately vertical plane passing through a line midway between the two rollers, and below a line drawn from the center of one roller to the center of the other. 95

2. In a device of the character described the combination of a roller having a periphery of yielding material and a roller having a corrugated periphery of rigid material positioned adjacent to each other with the axes parallel, and adapted to be rotated simultaneously in directions which will be downward along the line of the nearest approach of said peripheries to each other, and a partition of diminished thickness at the upper end positioned vertically approximately on the line of a vertical plane midway between the peripheries of said rollers, and below a line drawn between the centers of said rollers. 100
